UNITED STATES PATENT OFFICE.

ALVA HEYWOOD COOPER, OF ATLANTA, GEORGIA.

BLOW-OUT SHOE.

Application filed June 17, 1925. Serial No. 37,758.

To all whom it may concern:

Be it known that I, ALVA H. COOPER, a citizen of the United States, residing at Atlanta, in the county of Fulton and State 5 of Georgia, have invented a new and useful Blow-Out Shoe, of which the following is a specification.

This invention aims to provide a blow out shoe for vehicle tires which may be manufactured at trifling expense, the patch or shoe being so constituted that it will be flexible, strong, inexpensive, and well adapted to withstand the severe use to which devices 10 of the sort described are subject.

It is within the province of the disclosure 15 to improve generally and to enhance the utility of devices of that type to which the invention appertains.

With the above and other objects in view 20 which will appear as the description proceeds, the invention resides in the combination and arrangement of parts and in the details of construction hereinafter described and claimed, it being understood that 25 changes in the precise embodiment of the invention herein disclosed, may be made within in the scope of what is claimed, without departing from the spirit of the invention.

In the accompanying drawings:—

Figure 1 is a plan; Figure 2 is a section 30 on the line 2—2 of Figure 1, a part of the stitching being omitted; Figure 3 is a section on the line 3—3 of Figure 1, a part of the stitching being omitted.

The blow out shoe forming the subject 35 matter of this application comprises a body 1, a cover 2, a plurality of superposed layers 3 and 4 disposed between the body and the cover, said layers being of progressively decreasing areas and being housed completely 40 by the cover, and means for securing together the body, the cover, and said layers.

The smallest of said layers, to wit, the layer 4 is disposed next to the cover 2, the cover

being of less area than the body 1. The 45 means for securing together the body, the cover and the layers embodies a stitching extended in spiral form from a point adjacent to the axis of the cover to a point adjacent to the perimeter of the cover, the stitching being 50 designated by the numeral 5. Where the stitching makes a turn, it turns on a curve, as at 6, so that the stitching can be applied rapidly and conveniently in the process of manufacture.

The device may be fashioned out of any 55 desired material, canvas being suggested. It is to be observed that the layers 3 and 4 are housed by the cover 2, and a minimum number of open or exposed edges results. Owing to the specific way in which the cover 60 2 and the layers 3 and 4 are arranged with respect to each other and with respect to the body 1, strength and flexibility characterize the device.

What is claimed is:—

1. A blow out shoe comprising a body, a cover, a plurality of superposed layers disposed between the body and the cover, the smallest of said layers being disposed next 70 to the cover, and the cover being of less area than the body, said layers being of progressively decreasing areas and being housed completely by the cover, and means for securing together the body, the cover, and said 75 layers.

2. A blow-out shoe comprising a body, a cover, a plurality of superposed layers disposed between the body and the cover, said layers being of progressively decreasing areas and being housed completely by the cover, and a stitching extended in spiral form from a point adjacent to the axis of the cover to a point adjacent to the perimeter of the cover.

In testimony that I claim the foregoing as my own, I have hereto affixed my signature.

ALVA HEYWOOD COOPER.
